MULTIPLE METERING PUMP

Louis Bech, Woodside, N. Y.

Application July 19, 1944, Serial No. 545,560

5 Claims. (Cl. 103—173)

The present invention relates to a multiple pump with metering device for injection purposes and belongs to the type of pumps described in my copending application Serial No. 545,426, filed July 18, 1944. A pump according to that prior application comprises a plurality of pump units, each including a pump cylinder and plunger; the units are arranged equidistant from and parallel to the central axis of the pump, and a common adjustable valve controls the inlets to the cylinders and, thus, the output of each pump cylinder as to time and quantity. Contrary thereto, the present invention contemplates the provision of a pump wherein each plunger is provided with a face controlling the inlet port of the coordinate cylinder wherein, however, a common means is provided in order to position all the plungers equally so in relation to the inlet ports during the plunger reciprocation that the inlet ports will be closed by said plunger faces for desired lengths or portions of the plunger stroke. In the preferred form of the invention, each plunger has a head with a helical face to control an inlet port in the side wall of its cylinder; and the positions of the plungers in relation to the inlet ports can be peripherally adjusted by a common means so as to bring desired portions of the helical faces into registry with the inlet ports. In this manner it is possible to use, in the same pump, units with differently shaped controlling faces of the plungers and, therefore, different output characteristics. According further to the invention such common means may be actuated either by a part with originally peripheral movement or by a part with originally straight-lined movement.

Further details and objects of the invention will be apparent from the description given hereinafter and the accompanying drawings illustrating embodiments thereof by way of example.

In the drawings,

Fig. 1 is a longitudinal cross-section of a pump according to the invention;

Fig. 2 is a cross-section along line 2—2 of Fig. 1; and

Fig. 3 is a longitudinal cross-section of another embodiment.

Referring now to Fig. 1 of the drawings, the illustrated pump comprises a housing 10 consisting of three main parts, viz. a substantially hollow cylindrical body 11, a bottom 12 and a cover 13. The parts may be secured to one another by any suitable means such as screw bolts 14 and 15. The housing has a central axis *a—a*.

The housing body 11 is provided with an interior shell-like portion 16 in coaxial arrangement with the outer body wall 17, and connected thereto by an annular partition 18 of the housing space 19 which thus comprises an upper chamber 19 between the partition 18 and the cover 13 and a lower chamber 20 between the partition and the housing bottom 12. The chamber 19 has an opening 21 which may be threaded for the attachment of a pipe (not shown) connected to a fuel source. Similarly, chamber 20 has an opening 22 through which the chamber may be charged with lubricating oil. The partition 18 is provided with holes 23, preferably as many as there are engine cylinders to be charged by the pump, and evenly spaced from one another on a circle about the main axis *a—a*. In each hole a pump cylinder 24 is inserted which bears with a shoulder 25 on the bottom of a shallow recess 26 in the top surface of the partition and concentric with the hole 23. The cylinders 24 are flush with the top surfaces of the body 11 and the shell-like portion 16, so that the housing part 13 screwed on the body 11 covers the chamber 19 as well as the inner cylinder spaces 27.

Interiorly of the cover a conduit 28 is provided for each cylinder and in communication with the space 27 of the latter, and each conduit 28 is under the control of a check valve 29. The valves are biased by springs 30 each bearing on the bottom of a pipe connector 31 which is screwed at 32 into the cover 13. Interiorly of each cylinder 24 a plunger 33 is movable in an axial and a peripheral direction. For this purpose the plunger has a bore 34 reaching from its lower end far up towards the head of the plunger so that a connecting rod 35 bearing on the bottom of the bore 34 is free to move slightly out of alignment with the plunger axis. The head 36 of the plunger is formed as a portion of a hollow cylinder with a helical top face 37. The interior of the hollow cylinder is in communication with a peripheral groove 38 between the head portion 36 and the main body of the plunger. A port 39 is provided in the side wall of the cylinder 24 and under the control of the said plunger head 36 with its helical face 37 so that communication can be established through port 39 from the chamber 19 into the cylinder space 27. To the lower end of each plunger a pinion 40 is secured by any suitable means. In the case of the present embodiment the plunger is provided near its lower end with two parallel slots 41. A washer 42 is inserted into the slots in a radial direction

so as to engage the parallel faces of the slots 41 with its two parallel inner faces 43 as clearly shown in Fig. 2. The washer has also one or several projections 44 of its periphery. The pinion 40 is provided with a lower recess 45 fitting the outer contour of the washer 42. Another washer 46 bears on the pinion and a compression spring 47 is positioned between the lower face of the partition 18 and washer 46. The pressure exerted by spring 47 insures the connection between the pinion 40 and the plunger. This is due to the fact that the pinion is pressed on the washer 42 so as to be prevented from axial movement, while the washer projection 44 prevents relative rotation of the pinion and the washer 42. The washer in turn is prevented from angular and axial movement in relation to the plunger owing to its engagement in the slots 41 with parallel faces. The plungers are reciprocated by a drive similar to that described in my copending application Serial Number 545,426, filed July 18, 1944, that is to say, the lower portion 12 of the housing has an axial bore into which a bushing 48 is inserted to serve as a bearing for a drive shaft 49. The latter has a collar 50 with an inclined top face 51, and a cylindrical head 52 with its axis at right angles to the top face 51. The inner race 53 of a ball bearing 54 is mounted on the head 52 so as to engage the surface 51. The outer race 55 of the bearing carries a swash or wobble plate 56 with cup-shaped indentations 57 to receive therein the lower ends of the aforementioned connecting rods 35. Thus it will be clear that rotation of the shaft 49 will cause a cyclical oscillation of the swash plate 56 and thereby an axial reciprocation of each plunger with a phase displacement of each plunger in relation to the preceding one. The plungers may be turned by a common gear wheel 58 which is in engagement with all the pinions 40 secured to the plungers. The teeth of the pinions 40 are made of such length that the engagement with the gear wheel 58 is insured in any position of the plungers during their reciprocation. Gear wheel 58 bears against a lower face 59 of the shell-like housing portion 16 and a rod 60 is secured to the wheel 58 by means of a screw connection 61 so that by turning rod 60 the gear wheel 58 will be taken along so as to turn the pinions 40. Rod 60 projects through a bore 62 upward from the housing cover 13 and an arm 63 is secured to rod 60 as a means for controlling peripheral movement of the plungers.

The pump operates in the following manner. In order to apply the pump to an engine, shaft 49 will be coupled with a member rotating with half the R. P. M. of the engine if the latter is of the 4-stroke cycle type. The chamber 19 will be connected with its opening 21 to a fuel source and the lower pump space will be charged with a lubricant, for instance by connecting the opening 22 to an existing oil pump in which event a conduit 64 in the bottom portion of the housing may permit circulation of the oil back to the oil source. Furthermore, the pipe sockets 31 will be connected to the injection nozzles of the engine cylinders respectively. If now, shaft 49 is rotated the plungers will be reciprocated with a phase displacement as mentioned hereinbefore. Starting from the upper end position of one of the plungers, as for instance shown on the left-hand side of Fig. 1, its port 38 will be opened as soon as the helical face 37 has been sufficiently

lowered. Thereupon fuel from chamber 18 will fill the cylinder space 27 and upon the return stroke a certain quantity of the fuel interiorly of the space 27 will be forced out through conduit 28 against the force of the valve spring 30, and will be injected into the connected cylinder. The quantity of the fuel thus ejected is dependent on the portion of the helical face which passes and controls the port 38, that means if a lower portion of the piston head 36 passes the port 38 during the reciprocation of the plunger, the port will be opened for a larger portion of the stroke and less fuel will be discharged. Similarly, if the plunger is so turned that a higher portion of the plunger head 36 is in registry with its cylinder port 38, more fuel will be discharged during each plunger reciprocation.

The adjustment of the plungers in order to meter the quantity of ejected fluid requires a rotary movement transmitted to the plungers through a gear wheel mounted rotatably about the main pump axis. In the embodiment just described the gear wheel can be turned with the aid of an arm on the wheel shaft. In many instances of application of a pump according to the invention, it is desirable to render the plunger adjustment responsive to variations of the depression occurring in the manifold of an engine charged by the pump. In that event, it is advisable to apply means in order to convert a linear movement of the member responsive to the manifold depression into the rotary motion required for the mentioned gear wheel in order to adjust the pump plungers. Fig. 3 illustrates an embodiment comprising such means and a depression-responsive element in a particularly simple combination with the pump according to the invention. The general arrangement of the pump housing 101 with pump cylinders 102, and plungers 103 with pinions 104, is similar to the structure shown in Fig. 1. Also similar to the foregoing embodiment is the arrangement of the drive shaft 105 with swash or wobble plate 106 acting on the connecting rods 107. Also, the housing comprises a cover 108 containing conduits 109 for communication with valve chambers 110 to be connected to the cylinder nozzles of an engine to which the pump is to be applied. Above cover 108 a chamber is formed by a ring-shaped member 111 and a dome-shaped top 112. The parts are connected to each other by suitable means such as screws 113 which clamp, between the parts 111 and 112, a diaphragm 114 which in its circular portion is reinforced by discs 115. The chamber portion 116 between diaphragm 114 and the cover 108 is exposed to the atmospheric air through an opening 117, whereas the upper chamber portion 118 has an opening 119 for connection to the engine manifold. The diaphragm is biased by a spring 120 bearing against the bottom of an externally threaded cylindrical member 121, screwed into a nut 122 which bears with an external flange 123 on a shoulder 124 formed interiorly of an axial extension 125 of the top part 112. The extension 125 is interiorly threaded at 126 and a cap nut 127 is screwed into that threading so as to bear on the flange 123 of nut 122, thereby holding the parts in assembled position. Movement of the diaphragm is transmitted to the gear wheel 104. For this purpose a rod 128 is passed through the shell-like inner portion 130 of the housing 101 and guided in axial direction by a key 131 which engages a groove 132 in the inner

wall of the shell-like portion. The top end 133 of the rod 129 is threaded and projects upward from the housing cover 108 which for that purpose is provided with an axial bore 134. To the said upper end 133 of rod 129 the diaphragm is adjustably secured by a lower nut 135 and two upper nuts 136 and 137. The rod 129 is connected with its lower end projecting downward from the shell-like portion 130 to the gear wheel 128 by means whereby axial movement of the rod is transferred into rotary movement of the wheel 128. For that purpose the wheel is secured by screws 138 to the lower face of a cylindrical part 139 which encompasses the rod 129 and bears against the lower face 140 of the shell-like portion 130. The lower end of the rod 129 is provided with a high pitched helical groove 141 and a ball 142 projecting interiorly from the side wall of the cylindrical part 139 engages into said groove. Ball 142 is held into position by a set screw 143 screwed into a lateral bore 144 in the wall of the part 139. The gear wheel 128 with the part 139 secured thereto is supported from below by another ball 145 which rests on a cup-shaped member 146 provided in an axial bore 147 in the head of the drive shaft 105. A compression spring 148 is inserted between the bottom of the bore 147 and the cup 146 so as to render the support of the gear wheel 128 slightly resilient.

Now it will be clear that the diaphragm 114 will deflect upward or downward according to a change in the depression prevailing in chamber 118 owing to its connection with the engine manifold. The lowest position of the diaphragm is shown in Fig. 3 where the nut 135 bears upon the cover 108. The highest deflection is limited by the restraint of the spring 120 bearing on nut 136. If now, owing to an upward deflection of the diaphragm, the rod 129 connected thereto will be raised, the engagement of the ball 142 in the helical groove 141 will cause a turn of the cylindrical part 139 and the gear wheel 128 connected thereto. Rotation of the gear wheel will then be transmitted to the pinions 104 to adjust the plungers just as described with respect to the foregoing embodiment and such adjustment will be in response to a change of the depression of the engine manifold.

Having now described two embodiments of my invention, it will be apparent to those skilled in the art that many alterations and modifications of the mechanism illustrated and described are possible without departing from the spirit and essence of my invention which for this reason shall be limited only by the scope of the appended claims.

I claim:

1. A multiple injection pump comprising a substantially cylindrical housing with a central axis and including a cover, an interior and coaxial shell-like portion, and an annular partition between the housing wall and said shell-like portion so as to form an upper and a lower chamber each with a charging opening for fuel and oil respectively; a plurality of pump units, each unit including a cylinder secured to said partition and extending into said upper and lower chambers so as to be closed at its upper end by said cover, each cylinder being provided with an inlet port communicating with said upper chamber and with an outlet port for connection to a discharge, a plunger in each cylinder, each plunger having a helically-faced head to control the inlet port of its cylinder, a common driven means cyclically

movable about a center on said central axis to reciprocate said plungers, common means mounted in said housing in connection with said shell-like member to adjust the position of the plungers peripherally with respect to their cylinders, and a rod-like member movable in said shell-like portion and in connection with said common means to operate the latter.

2. A multiple injection pump comprising a substantially cylindrical housing with a central axis and including a cover, an interior and coaxial shell-like portion, and an annular partition between the housing wall and said shell-like portion so as to form an upper and a lower chamber each with a charging opening for fuel and oil respectively; a plurality of pump units, each unit including a cylinder secured to said partition and extending into said upper and lower chambers so as to be closed at its upper end by said cover, each cylinder being provided with an inlet port communicating with said upper chamber and with an outlet port for connection to a discharge, a plunger in each cylinder, each plunger having a helically-faced head to control the inlet port of its cylinders, a common driven means cyclically movable about a center on said central axis to reciprocate said plungers, common means mounted in said housing in connection with said shell-like member to adjust the position of the plungers peripherally with respect to their cylinders, and a vacuum-responsive means in connection with said common means to actuate the latter.

3. A multiple injection pump comprising a substantially cylindrical housing with a central axis and including a cover, an interior and coaxial shell-like portion, and an annular partition between the housing wall and said shell-like portion so as to form an upper and a lower chamber each with a charging opening for fuel and oil respectively, a plurality of pump units, each unit including a cylinder secured to said partition and extending into said upper and lower chambers so as to be closed at its upper end by said cover, each cylinder being provided with an inlet port communicating with said upper chamber and with an outlet port for connection to a discharge, a plunger in each cylinder, each plunger including a body portion and, for controlling said inlet port of the coordinate cylinder, a head with a helical end face and a peripheral annular groove between said body and said head, said head being of a hollow cylindrical shape and provided with a communication of its interior with said groove, a common driven means cyclically movable about a center on said central axis to reciprocate said plungers, common means mounted in said housing in connection with said shell-like member to adjust the position of the plungers peripherally with respect to their cylinders, and a member movable in said shell-like portion and in connection with said common means to operate the latter.

4. A pump as claimed in claim 3, wherein said communication between the interior of each plunger head and its peripheral groove is constituted by a longitudinal slot in the wall of said head between the lowest and the highest points of said helical face and extending from said face into said groove.

5. A multiple injection pump comprising a substantially cylindrical housing with a central axis and including a cover, an interior and coaxial shell-like portion, and an annular partition between the housing wall and said shell-like portion so as to form an upper and a lower chamber

each with a charging opening for fuel and oil respectively, a plurality of pump units, each unit including a cylinder secured to said partition and extending into said upper and lower chambers so as to be closed at its upper end by said cover, conduits to connect each cylinder to said upper chamber and to a discharge, a hollow plunger in each cylinder, open at the bottom and closed near its head, a driven wobble plate cyclically movable about a center on said central axis, a 10 rod ball-headed at both its ends for each of the

plungers and bearing with one of its ends against said wobble plate and with its other end interiorly of said plunger against the closure thereof, a spring between each plunger and the housing to urge said plunger towards said wobble plate, adjustable means in controlling relationship to the conduits connecting said cylinders to said upper chamber, and common means mounted in said housing in connection with said shell-like member to adjust said adjustable means.

LOUIS BEEH.
